wherein A represents an acyl group selected from ar-
oyl, substituted aroyl, lower alkanoyl and the residue
of a heterocyclic acid chloride, or a 4,6-substituted-s-
triazinyl group in which the 4 and 6 positions can con-
tain an $-N(CH_2CN)_2$ group, are bleach activators of
high strength and good storage stability in peroxygen
bleaching compositions.

IMINODIACETONITRILE DERIVATIVES AS PEROXYGEN BLEACH ACTIVATORS

This invention relates to bleaching compositions, and more particularly to improved bleaching compositions containing hydrogen peroxide releasing compounds and activators for such compounds as defined below, and to compositions of the activators and hydrogen peroxide releasing compounds with detergents.

The invention provides improved bleaching compositions comprising hydrogen peroxide or a hydrogen peroxide releasing compound and an effective amount of an activator. The activators are derivatives of iminodiacetonitrile represented by Formula I:

wherein A is an acyl group selected from aroyl, substituted aroyl, lower (C_1-C_5) alkanoyl and the residue of a heterocyclic carboxylic acid chloride; or a 4,6-disubstituted-s-triazinyl group in which the substituent groups are selected from amino, diethylamino and $-N(CH_2CN)_2$ groups.

U.S. Pat. No. 2,927,840 discloses bleaching compositions comprising a peroxygen compound and an organic nitrile, including iminodiacetonitrile. The use of various N-acyl compounds as bleach activators has previously been disclosed. For example, French Pat. No. 1,583,330 discloses the use of N-acyl derivatives of heterocycles such as imidazole, pyrazole and triazole, and British Pat. No. 1,046,251 discloses the use of N-acyl derivatives of pyridazine, triazole and pyrazole as peroxygen salt activators in bleaching compositions for textile materials. French Pat. No. 1,489,926 discloses the use of the acyl-containing non-heterocycles N-acetyl-N-methyl-p-toluenesulfonamide and N-propionyl-N-methyl-p-toluenesulfonamide. Indeed, a perborate bleaching composition containing an activator such as any of these can be shown to remove a greater percentage of tea stain from a textile material than the same bleaching composition in which activator is omitted.

However, many peroxygen bleaching compositions containing such activators have not proved satisfactory for one or more reasons, such as inadequate bleaching or instability at 50° to 70°C., the typical working temperature range of modern laundry washing machines; or because of unsatisfactory compatibility with detergents or other materials with which associated; or because of objectionable odor; or because the activators tend to deteriorate during storage of the bleaching composition under a variety of conditions of temperature and humidity.

To be useful, a bleach activator must, in particular, maintain its high activity in a formulation over a long period of time as such or in the presence of a peroxyde releasing agent or in the presence of a detergent composition. Commercial products are often subject to storage for considerable periods of time in hot, humid warehouses or on the supermarket shelf before consumer use, and to be satisfactory the activity must be maintained without appreciable loss during such periods.

Thus, there is a continued need for a variety of improved bleaching compositions, especially those which maintain their activity over such long periods of time

and which are stable and effective in the presence of various detergents as used in home and commercial laundries.

It has now been found that certain derivatives of iminodiacetonitrile, represented by Formula I, provide new and improved activators for peroxygen bleaching compositions. These new bleaching compositions exhibit good bleaching effectiveness at relatively low temperatures, eg, 10°C. to 70°C. Moreover, because of the good storage stability of the activators, the bleaching compositions may be stored for surprisingly long periods of time under a wide variety of temperature/humidity conditions without significant loss of activity.

A preferred species of activator within the definition of Formula I is benzoyliminodiacetonitrile (Formula II):

As shown in accompanying Example 2, a perborate bleaching composition containing (II) as the activator removes more than twice as much tea stain from the textile as the same bleaching composition without the activator. Furthermore, (II) has excellent storage stability as illustrated herein.

An additional advantage of the compositions of the invention is the provision of dry oxygen bleaching compositions which not only exhibit good bleaching activity at relatively low-water temperatures, but also are safer and easier to handle than liquid bleach products. They are relatively safe for all fabrics as well as for dyes thereon, for human and animal hair bleaching compositions, and exhibit germicidal activity. In addition, the compositions are useful for bleaching ground wood pulp.

As is known to those skilled in the art, ordinary monoamides ($R-CO-NR'R''$) such as N,N-dimethylacetamide are inactive as peroxygen salt bleach activators. A unique aspect of the compounds which are the peroxygen salt bleach activators of this invention is that, unlike the preponderance of disclosed types, these compounds do not rely on the structural

unit as would be found in molecular structures of known activators such as, for example:

(benzoyldimethylhydantoin)

(N-benzoysuccinimide)

(N-acetylsaccharin)

The phenomenon is evidenced by the excellent activity of the compounds of this invention. It is surprising, however, that this effect is absent in the case of the analogous propionitrile homologs, which are inactive as peroxygen salt bleach activators (Examples 10, 11 and 12 below). We are thus concerned with a very specific effect obtained with compounds of Structure I.

The novel bleach activators of this invention can be prepared by well known methods. Benzoyliminodiacetonitrile, for example, can be prepared by reaction of benzoyl chloride with iminodiacetonitrile according to the following equation:

Other aroyl, substituted aroyl, alkanoyl and heterocyclic acyl derivatives can be prepared similarly from the appropriate carboxylic acid halides (or anhydrides in some instances).

Typical carboxylic acid halides (or anhydrides) that can be chosen for reaction with the iminodiacetonitrile to give the products of this invention include those such as:

- p-chlorobenzoyl chloride
- salicyloyl chloride
- o-nitrobenzoyl chloride
- p-nitrobenzoyl chloride
- o-bromobenzoyl chloride
- terephthaloyl chloride
- p-fluorobenzoyl chloride
- m-methoxybenzoyl chloride
- 2,4-dimethylbenzoyl bromide
- p-(trifluoromethyl)benzoyl chloride
- o-methylbenzoyl bromide
- p-ethylbenzoyl bromide
- 1-naphthoyl chloride
- 3-hydroxy-2-naphthoyl chloride
- acetic anhydride
- propionic anhydride
- propionyl chloride
- butyryl chloride
- butyric anhydride
- caproic anhydride
- caproyl chloride
- furoyl chloride
- thenoyl chloride
- nicotinoyl chloride
- picolinoyl chloride

cyanuric chloride, and the like.

The preferred species of the invention are those derived from aromatic carboxylic acid halides, cyanuric chlorides, and lower aliphatic carboxylic acid halides.

The bleaching compositions of the invention contain the activating compound and the hydrogen peroxide releasing compound in a molar ratio ranging from about 1:1 to about 1:10, respectively, with a preferred range of about 1:1 to 1:3. The actual ratio of activator to bleach can, of course, be varied widely for varying applications.

The oxygen bleaches useful in these bleaching compositions are hydrogen peroxide and organic peroxides and inorganic peroxygen salts that liberate hydrogen peroxide in water. Examples of peroxide bleaching compounds are urea peroxide, benzoyl peroxide, methyl ethyl ketone peroxide, and the like. Examples of inorganic peroxygen bleaching compounds are alkali metal perborates, percarbonates, perphosphates, persulfates, monopersulfates, and the like. Mixtures of two or more bleaching compounds can, of course, be used if desired.

Although the various peroxide releasing compounds as mentioned above may be used in the compositions of the invention, preferred peroxide releasing compounds are sodium perborate (for economic considerations) and sodium percarbonate (for ecological considerations).

The activated bleach compositions of the invention are useful for bleach applications for various substrates including fabrics, particularly when incorporated with detergent compositions for household or commercial laundering purposes. A most important property of such detergent compositions is the ability to remove stains including food stains such as those of coffee, tea, wine and the like as well as to maintain purity of white in uncolored textiles. Aside from food stains, soiling in general may be removed such as grass stains, urine and the like.

In addition to the detergent, peroxygen releasing compound and peroxygen bleach activator, such detergent compositions may contain other optional additives such as germicides, fungicides, enzymes, optical brighteners, colorants, perfumes, thickeners, emulsion or suspension stabilizers, and the like, including "builders," such as sodium phosphate, salts, carbonates, silicates, and the like as usually encountered in the art.

The detergent component of such activated bleach compositions may be any of the conventional types such as anionic, cationic, nonionic or amphoteric.

Examples of typically suitable anionic detergents include the alkali metal or alkaline earth metal salts of higher alkylbenzene sulfonates, olefin sulfonates, higher alkyl sulfates and higher fatty acid monoglyceride sulfates.

Examples of typically suitable cationic detergents include tetraalkyl ammonium salts in which one of the alkyl groups contains approximately 12 to 18 carbons such as dodecyltrimethylammonium chloride or ethylidimethyloctadecylammonium methosulfate.

Examples of suitably typical amphoteric detergents are those detergent compounds possessing both cationic and anionic sites and include, for example, amino fatty acids such as dimethylaminopropionic acid and iminodifatty acids such as methyliminodilauric acid.

Examples of typical nonionic detergents include polyglycol ethers of alkanol amides of higher fatty acids

and also polyglycol ethers of higher alkanols and higher fatty acids.

Bleaching compositions may generally be used also for their germicidal properties in various applications for control of microbial growth. Applications may be made to any surface or substrate where such control is desired.

The treatment of swimming pool water and swimming pool surfaces with the compositions of the invention is especially efficacious since the usually lower temperatures of these environments prevent effective use of other antimicrobial agents. A related utility is the treatment of water supplies to render the same fit for human consumption or for industrial use, such as the sanitization of field water for consumption by military personnel or the treatment of industrial process water so it can be reused in industrial processes or by the surrounding community. The compositions also may be employed in admixture with detergents for use as home or industrial germicidal detergents, or in hair bleaching compositions containing peroxygen compounds.

The following examples will serve to illustrate the invention.

EXAMPLE 1

Preparation of Benzoyliminodiacetonitrile

A mixture of 4.0 grams (0.04 mole) of iminodiacetonitrile and 5.8 grams (0.04 mole) of benzoyl chloride in 50 ml of dry dimethylformamide is heated with occasional stirring over a steam bath for 1 hour. This solution is then cooled, diluted with about 150 ml of water and the resultant white precipitate collected and recrystallized from methanol. Yield 6.8 grams or 85% of theory, mp 124° - 125.5°C.

Other aroyl derivatives of iminodiacetonitrile are obtained similarly by use of an equivalent amount of another aroyl halide in place of benzoyl chloride.

EXAMPLE 2

Evaluation of Benzoyliminodiacetonitrile as Activator for Sodium Perborate

A bleaching composition was prepared using the benzoyliminodiacetonitrile of Example 1 and sodium perborate in a molar ratio of 1:1.1 and the bleaching effectiveness of this composition determined by the following test procedure:

Five-gram swatches of desized, 80 × 80 cotton fabric are stained with tea in the following manner. Five tea bags are placed in one liter of water and boiled for five minutes. The swatches are then immersed in the tea and the boiling is continued for another five minutes. The swatches are then removed from the tea, wrung out, dried at 200°-215°F., rinsed in cold water and again dried.

Two of the stained cotton swatches are placed in a stainless steel Terg-O-Tometer manufactured by U.S. Testing Company. One liter of distilled water at 120°F. is introduced and 40 grams of unstained cotton fabric

5 are added so as to provide a typical household washing machine water-to-cloth ratio of about 20 to 1. Then 2.0 grams of anionic detergent available commercially as "Tide" is added, followed by 0.33 gram sodium perborate and 0.60 gram of benzoyliminodiacetonitrile. The 10 Terg-O-Tometer is operated at 100 cycles per minute for 15 minutes at a temperature of 120°F. The swatches are then removed, rinsed with cold water and dried at room temperature.

15 Both before and after laundering, reflectance readings of the swatches are taken on a Hunter Model 25M Reflectometer with a blue filter. The swatches are backed with a white porcelain plate and read once on both sides. Fluorescent effect is excluded from all readings.

20 The reflectance readings are averaged and the percent stain removal is obtained in accordance with the following formula in which R is the symbol for reflectance:

25 Total % stain removal =

$$\frac{R \text{ (bleached)} - R \text{ (stained)}}{R \text{ (unstained)} - R \text{ (stained)}} \times 100$$

30 Control runs are also made using the described amounts of the detergent and sodium perborate with no activator.

35 It was found that the bleaching composition of this example removed an average of 61.8% of the stain from the swatches, whereas the control composition removed only 26% of the stain. Similar results are obtained if one uses a nonionic detergent such as "All" detergent.

EXAMPLES 3-9

Testing of Aroyl Derivatives of Iminodiacetonitrile as Activators for Sodium Perborate

Bleaching compositions comparable to the bleaching compositions of Example 2 were prepared in Examples 3-9. In each case, the formulation was such as to provide 2.0 grams of Tide detergent, 0.33 gram of sodium perborate and the indicated amount (grams) of activator per liter of solution. The molar ratio of activator to sodium perborate in each instance was 1:1.1. The test procedure was the same as described in Example 2. Results of the testing in Examples 3-9 as well as Example 2 are summarized in Table I. As shown in the Table, the control result is apt to vary somewhat from one set or series of tests to another due to variations in the cloth and the tea used to produce the stains.

TABLE I

Example No.	Bleach Activator Structure	Wt. of Activator (Grams)	% Stain Removed
2		0.60 g	61.8 (26.0) ¹
3		0.72 g	59.9 (33.7) ¹

TABLE I (CONTINUED)

Example No.	Bleach Activator Structure	Wt. of Activator (Grams)	% Stain Removed
4		0.70 g	55.0 (33.7) ¹
5		0.67 g	60.3 (40.6) ¹
6		0.81 g	53.6 (31.7) ¹
7		0.66 g	57.8 (31.7) ¹
8		0.73 g	58.8 (30.7) ¹
9		0.69 g	58.8 (30.7) ¹

¹Control result

EXAMPLES 10-12

Testing of Aroyl Derivatives of Iminodipropionitrile as Activators for Sodium Perborate

40

In the testing of the aroyl derivatives of iminodipropionitrile, bleaching compositions comparable to the bleaching compositions of Example 2 were prepared in

Examples 10-12. In each case, the formulation was such as to provide 2.0 grams of Tide detergent, 0.33 gram of sodium perborate and the indicated amount (grams) of activator per liter of solution. The mole ratio of activator to sodium perborate in each instance was 1:1:1. The test procedure was the same as described in Example 2. Results of the testing in Examples 10-12 are summarized in Table II.

TABLE II

Example No.	Bleach Activator Structure	Wt. of Activator (Grams)	% Stain Removed
10		0.68 g	32.1 (33.7) ¹
11		0.82 g	26.3 (33.7) ¹
12		0.78 g	29.0 (33.7) ¹

(¹)
Control test result

The results in Table II show that the aroyl derivatives of iminodipropionitrile are ineffective as activators for sodium perborate.

EXAMPLE 13

Evaluation of Benzoyliminodiacetonitrile as Activator for Sodium Percarbonate

Following the procedure of Example 2, except for the use of 0.35 gram of sodium percarbonate instead of 0.33 gram of sodium perborate, 53.2% of the tea stain was removed. The control test in this case showed 32.6% stain removed.

EXAMPLE 14

Storage Stability of Benzoyliminodiacetonitrile

The storage stability of benzoyliminodiacetonitrile in a dry bleaching composition was determined by testing the bleaching effectiveness of such a composition after three months storage (a) at room temperature in a closed container, and (b) at 80°F. and 80% relative humidity in an open container with the bleaching effectiveness of a freshly prepared composition. The bleach composition and the test procedure were the same as that described in Example 2, except that the dry composition in each case was prepared by mixing the dry ingredients (detergent, perborate and benzoyliminodiacetonitrile) and, after storage, adding the mixture to the bleach bath water. The freshly prepared composition was made as described in Example 2 (by adding the dry ingredients, separately, to the bleach bath water).

TABLE III

Bleach Composition	% Stain Removed
Freshly Prepared	66.2 (41.0) ¹
Stored 3 Months at RT in Closed Container	69.6
Stored 3 Months at 80°F. and 80% RH in Open Container	53.9
¹ Control test result	

It is seen that the benzoyliminodiacetonitrile maintains its full activity over the storage period in the closed container and about 50% of its activity in the open container.

EXAMPLE 15

Preparation of 2-(Biscyanomethylamino)-4,6-diamino-s-triazine

2,4-Diamino-6-chloro-s-triazine (14.2 g, 0.1 mole), iminobisacetonitrile (10.0 g, 0.1 mole), 0.84 g sodium bicarbonate and 100 ml dioxane were refluxed for about 1 hour. The dioxane solution was decanted away from the gummy solid and diluted with an equal volume of water. A white, crystalline solid (2.10 g, mp 188°-194°C.) was isolated and identified by infrared spectroscopy as the subject compound.

35
40
45

EXAMPLE 16

Preparation of 2,4,6-Tris(biscyanomethylamino)-s-triazine

15 Cyanuric chloride (4.7 g, 0.025 mole) was added portionwise to a solution of iminobisacetonitrile (14.3 g, 0.15 mole) in 100 ml dimethylformamide. The resulting solution was heated to 150°C., held for about 30 minutes, cooled to room temperature and poured over ice. The solid obtained was suspended in 100 ml dioxane, heated and filtered, resulting in a solid, mp 218°-222°C. (5.2 g, 58% yield). Recrystallized from acetonitrile, yielded white needle-like crystals, mp 230°-232°C.

25

EXAMPLE 17

Preparation of 2,6-Diethylamino-4-bis(cyanomethyl)amino-s-triazine

2,6-Dichloro-4-bis(cyanomethyl)amino-s-triazine (2.0 g, 0.008 mole) was added to 10 ml diethylamine in 20 ml dimethylacetamide at steam bath temperature. After about 5-10 minutes, a solid precipitated and the reaction mixture was drowned in water. The solid was filtered and recrystallized from methanol, mp 94°-96°C.

40

EXAMPLE 18

Preparation of 2,4-Bis(cyanomethyl)amino-6-diethylamino-s-triazine

50

55

60 In a manner similar to Example 17, 4.0 g (0.0013 mole) of 2-chloro-4,6-bis(cyanomethyl)amino-s-triazine was added to 10 ml diethylamine in 25 ml dimethylacetamide. After 20 minutes, the reaction mixture was poured over ice and the resulting solid filtered. Recrystallization from methanol gave needles, mp 163°-164°C.

65

Testing of Triazinyl Derivatives as Activators for Sodium Perborate

Using the triazinyl derivatives of Examples 15-18, bleaching compositions comparable to the bleaching compositions of Example 2 were prepared and tested by the procedure described in Example 2. In each case, the formulation was such as to provide 2.0 grams of Tide detergent, 0.33 gram of sodium perborate and the indicated amount (grams) of activator per liter of solution. The mole ratio of activator to sodium perborate in each instance was 1:1.1. Results of the testing are summarized in Table IV.

TABLE IV

Compound of Example No.	Wt. (g.) Activator	% Stain Removed	15
15	0.61	65.4	(40.3) ¹
16	1.1	49.7	(39.0) ¹
	0.5	50.2	"
	0.1	44.8	"
17	0.95	41.4	(39.0) ¹
18	1.0	45.5	(39.0) ¹

¹Control result

EXAMPLE 19

Preparation of N,N-dicyanomethylpropionamide

20 g (0.2 mole) of iminobisacetonitrile and 75 ml of propionic anhydride were heated to reflux for 4 hours and the hot solution poured over ice. The solution was then neutralized with concentrated ammonium hydroxide, extracted with 150 ml benzene, and the dried benzene solution evaporated to give the product as an amber oil.

EXAMPLE 20

Preparation of N,N-dicyanomethylthiophene Carbonamide

2-Thiophene carboxyl chloride (10 g, 0.067 mole), iminodiacetonitrile (6.7 g, 0.067 mole) and 50 ml dimethylformamide were heated for 2 hours at steam bath temperatures and the hot solution poured over ice. The resulting solid was filtered, suspended in 500 ml methanol, decolorized, and then cooled to give 8.4 g (58%) of white crystals, mp 137°-138.5°C.

EXAMPLE 21

Preparation of N,N-dicyanomethylfuran Carbonamide

2-Furoyl chloride (13.2 g, 0.1 mole), iminodiacetonitrile (10 g, 0.1 mole) and 100 ml dimethylformamide were heated for about 2 hours at steam bath temperatures and the reaction mixture poured into ice. The resulting solid was filtered, suspended in 250 ml methanol, decolorized and filtered. Long white needle-like crystals formed which were washed with methanol and dried; 14.2 g, mp 112°-113.5°C.

Testing of Alkanoyl and Heterocyclic Carboxylic Acid Chloride Derivatives as Activators for Sodium Perborate

Using the compounds of Examples 19-21, bleaching compositions comparable to the bleaching compositions of Example 2 were prepared and tested by the procedure described in Example 2. In each case, the formulation was such as to provide 2.0 grams of Tide detergent, 0.33 gram of sodium perborate and the indicated amount (grams) of activator per liter of solution. The mole ratio of activator to sodium perborate in each instance was 1:1.1. The test results are given in Table V.

TABLE V

Compound of Example No.	Wt. (g.) Activator	% Stain Removed
19	0.45	62.8 (40.3) ¹
20	0.61	59.9 (32.6) ¹
21	0.57	58.1 (32.6) ¹

¹Control result

I claim:

1. A bleaching composition comprising hydrogen peroxide or a hydrogen peroxide releasing compound of the group of organic peroxides and inorganic peroxogen salts and an activating amount of an iminodiacetonitrile compound represented by the formula:

wherein A is an acyl group selected from aroyl, substituted aroyl, lower alkanoyl and the residue of a heterocyclic carboxylic acid halide; or a 4,6-disubstituted-triazinyl group in which the substituent groups are selected from amino, diethylamino and bis(cyanomethyl)amino groups.

2. A composition according to claim 1 wherein A in the iminodiacetonitrile compound represents an unsubstituted benzoyl or naphthoyl radical or a substituted benzoyl or naphthoyl radical having a substituent selected from halo, nitro, hydroxy, carboxy, C₁-C₅ alkyl, C₁-C₅ alkoxy and halosubstituted C₁-C₅ alkyl groups.

3. A composition according to claim 2 wherein the iminodiacetonitrile compound has the formula:

4. A composition according to claim 2 wherein the iminodiacetonitrile compound has the formula:

5. A composition according to claim 2 wherein the iminodiacetonitrile compound has the formula:

6. A composition according to claim 2 wherein the iminodiacetonitrile compound has the formula:

13

7. A composition according to claim 1 wherein A in the iminodiacetonitrile compound is a C₁-C₅ alkanoyl group.

8. A composition according to claim 7 wherein the iminodiacetonitrile compound has the formula:

9. A composition according to claim 1 wherein A in the iminodiacetonitrile compound is the residue of a heterocyclic carboxylic acid halide selected from furoyl, thenoyl and picolinoyl groups.

10. A composition according to claim 9 wherein the iminodiacetonitrile compound has the formula:

14

11. A composition according to claim 1 wherein A in the iminodiacetonitrile compound is a 4,6-disubstituted triazinyl group selected from

4,6-diaminotriazinyl,

4,6-bis(diethylamino)triazinyl,

4-diethylamino-6-bis(cyanomethyl)aminotriazinyl,

and

4,6-bis[di(cyanomethyl)amino]triazinyl groups.

12. A composition of claim 11 wherein the iminodiacetonitrile compound has the formula

13. A composition according to claim 1 containing a detergent.
